UNITED STATES PATENT OFFICE.

AUGUST M. DUVAL AND PORTER C. FARRIS, OF BRAZIL, INDIANA.

FURNACE.

Application filed October 4, 1921. Serial No. 505,429.

To all whom it may concern:

Be it known that we, AUGUST M. DUVAL and PORTER C. FARRIS, citizens of the United States, residing at Brazil, in the county of Clay and State of Indiana, have invented certain new and useful Improvements in Furnaces, of which the following is a specification.

This invention relates to furnaces and more particularly to coal direct fired furnaces.

The primary object of this invention is to provide a furnace of this character so constructed as to burn successfully a kiln of brick or other clay products with the minimum amount of fuel in the least number of hours without injury to the ware.

A further object of this invention is to provide a furnace so constructed as to supply pre-heated air to the fuel used which will materially assist in combustion.

A further object of this invention is to provide a furnace which will eliminate kiln hub expansion by reason of a large column of air being forced through air passages of the kiln hubs to the furnace, thereby prolonging the life of the kiln.

A still further object is to provide a furnace of this character which may be used in connection with all types of kilns.

With these and other objects in view, the invention consists in certain novel features of construction as hereinafter shown, described and claimed.

In the accompanying drawings:

Figure 1 represents a front elevation of a furnace embodying this invention, with the doors and frames omitted.

Figure 2 is a horizontal section taken on the line 2—2 of Fig. 1, and

Figure 3 is a detail vertical section taken on the line 3—3 of Fig. 2.

In the embodiment illustrated a furnace 1 is shown, designed to be used in connection with any kind or type of kiln and which is equipped with the usual ash box 2 having a fire box 4 arranged there-over provided with a grate 3 between them. The fire box has the usual front opening for the fuel as shown at 5.

A cold air feed pipe 10 of suitable size, is preferably mounted across the front of the furnace as is shown clearly in Fig. 1 and has leading therefrom at longitudinally

spaced points, lateral pipes or flues 11 and 12 which extend downwardly at points on opposite sides of the fire box opening 5. Leading from each of said lateral flues 11 and 12, are air flues 13, 14 and 15 which connect with built in air passages through the side walls of the furnace 1 and open into the fire box above and underneath the grates. The two pipes or flues 13 and 14 may be termed "the pre-heated air flues" and are arranged in the same horizontal plane, while the flues 15, one of which is arranged at each side of the fire box may be termed "the pre-heated air flues for air combustion" and are positioned in a plane above the flues 13 and 14 as is shown clearly in Fig. 3. However, flues 15 may be placed underneath and near the center of the grates to supply air for the burning of such fuel as slack or lignite coal.

The arrangement of the flues 13, 14 and 15 in the side walls of the furnace 1 operates to eliminate expansion in the kiln hubs thereby prolonging the life of the kiln and at the same time the pre-heated air fed through these flues to the fire box assists in the burning of the fuel used, which will result in effecting a saving of from fifteen to twenty per cent in fuel, while the principle of forced draft will advance the burning time of the ware in the kiln in connection with which the furnace is employed from fifteen to twenty per cent.

Each of the flues 13, 14 and 15 is equipped with a valve or damper 16 provided with an operating handle 17, as is shown clearly in Fig. 3.

The air supplied through the flues 13, 14 and 15 is furnished mechanically by an exhaust fan operated by any mode of power and which is not shown in the drawing.

The pre-heated air flues 15 are designed to be used for the combustion of gases from the fuel bed passing into the combustion chamber at the end of the grate and these gases are ignited by admission of oxygen supplied mechanically and controlled by the valve 16 with which the flues 15 are equipped.

The preferred embodiment of the invention is disclosed in the drawings and set forth in the specification, but it will be understood that any modifications within the scope of the claimed invention may be made

in the construction without departing from the principle of the invention or sacrificing any of its advantages.

We claim:

5. 1. In a furnace structure a body portion having means to constitute a fire box, bridge wall, an ash pit and grate bars interposed between the box and pit, said body portion further provided at each side of the fire box 10 with a pair of horizontally disposed air conducting flues leading from the front of the body portion, the flues of each pair opening into the front and rear of the fire box through one side thereof above the grate bars forwardly of the bridge wall, and said body portion further provided at each side of the fire box with an air conducting flue 15 leading from the front of the body portion and opening into the ash pit through a side wall thereof below the grate bars forwardly of and independent of the bridge wall.

2. In a furnace structure a body portion having means to constitute a fire box, a bridge wall, an ash pit and grate bars interposed between the box and pit, said body portion further provided at each side of the fire box with a pair of horizontally disposed air conducting flues leading from the front of the body portion, the flues of each 25 pair opening into the front and rear of the fire box through one side thereof above the grate bars forwardly of the bridge wall, and said body portion further provided at each side of the fire box with an air conducting flue 30 leading from the front of the body portion and opening into the ash pit through a side wall thereof below the grate bars forwardly of and independent of the bridge wall, each of the flues opening into the ash pit having its discharge end positioned centrally with respect to the discharge ends of a pair of flues opening into the fire box.

3. In a furnace structure a body portion having means to constitute a fire box, a bridge wall, an ash pit and grate bars interposed between the box and pit, said body portion further provided at each side of the fire box with a pair of horizontally disposed air conducting flues leading from the front 45 of the body portion, the flues of each pair opening into the front and rear of the fire box through one side thereof above the grate bars forwardly of the bridge wall, and said body portion further provided at each side of the fire box with an air conducting flue 50 leading from the front of the body portion and opening into the ash pit through a side wall thereof below the grate bars forwardly of and independent of the bridge wall, each 55 of the flues opening into the ash pit having its discharge end positioned centrally with respect to the discharge ends of a pair of flues opening into the fire box, the inner portions of the flues of said pairs of flues curving 60 towards the fire box, and the inner portions 65 of each of said other flues curving towards the ash pit.

4. In a furnace structure a body portion having means to constitute a fire box, a bridge wall, an ash pit and grate bars interposed between the box and pit, said body portion further provided at each side of the fire box with a pair of horizontally disposed air conducting flues leading from the front of the body portion, the flues of each pair 70 opening into the front and rear of the fire box through one side thereof above the grate bars forwardly of the bridge wall, and said body portion further provided at each side of the fire box with an air conducting flue 75 leading from the front of the body portion and opening into the ash pit through a side wall thereof below the grate bars forwardly of and independent of the bridge wall, an independent air supply pipe arranged exteriorly of the front of said body portion and communicating with the outer end of each flue and further provided with a controlling valve, and an air feed pipe common to said supply pipes.

5. In a furnace structure a body portion having means to constitute a fire box, a bridge wall, an ash pit and grate bars interposed between the box and pit, said body portion further provided at each side of the fire box with a pair of horizontally disposed air conducting flues leading from the front of the body portion, the flues of each pair opening into the front and rear of the fire box through one side thereof above the grate bars forwardly of the bridge wall, and said body portion further provided at each side of the fire box with an air conducting flue 90 leading from the front of the body portion and opening into the ash pit through a side wall thereof below the grate bars forwardly of and independent of the bridge wall, the said flues communicating with the ash pit 95 arranged for a portion of their length above the other of said flues and each having its inner portion of L-shape contour and depending from the remaining portion thereof.

6. In a furnace structure a body portion having means to constitute a fire box, a bridge wall, an ash pit and grate bars interposed between the box and pit, said body portion further provided at each side of the fire box with a pair of horizontally disposed air conducting flues leading from the front of the body portion, the flues of each pair opening into the front and rear of the fire box through one side thereof above the grate bars forwardly of the bridge wall, said body portion further provided at each side of the fire box with an air conducting flue leading 115 from the front of the body portion and opening into the ash pit through a side wall thereof below the grate bars, forwardly of and independent of the bridge wall, the end 120 of the flues curving towards the fire box, and the inner portions 125 of each of said other flues curving towards the ash pit.

trance ends of the flues which open below the fire box being arranged above the entrance ends of the other of the flues, a pair of vertically disposed flues arranged at the front of said body portion, a series of branches leading from each of said vertical flues to the entrances of the flues at each side of the fire

box, a common air supply pipe for said vertical flues, and a damper mounted in each of said branches.

In testimony whereof, we affix our signatures hereto.

AUGUST M. DUVAL.
PORTER C. FARRIS.
